UNITED STATES PATENT OFFICE.

HENRY L. HASKELL, OF LUDINGTON, MICHIGAN.

DESIGN FOR A GAME-BOARD.

SPECIFICATION forming part of Design No. 33,714, dated December 11, 1900.

Application filed July 14, 1900. Serial No. 23,683. Term of patent 7 years.

To all whom it may concern:

Be it known that I, HENRY L. HASKELL, a citizen of the United States, residing at the city of Ludington, in the county of Mason and State of Michigan, have invented and produced a Design for Game-Boards, of which the following is a specification.

This invention relates to a design for a game-board.

10 The object of the invention is to provide a design for a combination game-board.

The design is fully illustrated in the accompanying drawings, in which—

15 Figure 1 is a perspective view of the obverse side of a game-board according to my design. Fig. 2 is a perspective view of the reverse of my design for a game-board.

The leading features of my design will now be pointed out.

20 As shown in the drawings, the leading features of my design consist of a game-board polygonal in outline. The board consists of an outer field A, which is provided with a

rim B, and an inner field C. At the center of the field C is a depression E, and arranged around the same at suitable intervals are projecting pins F. There are also arranged at suitable intervals around the field C points of a scroll design. On the reverse side of the board is a square field D, which is divided 25 into squares or blocks D'D', the lines d d', crossing each other at right angles, dividing the field D into a second set or series of squares.

Having thus described my design, what I 30 claim is—

The design for a game-board, substantially as described and shown.

In witness whereof I have hereunto set my hand and seal in the presence of two witnesses.

HENRY L. HASKELL. [L. S.]
